CLAIM

What is claimed is the ornamental design for a purging bottle, as shown and described.

DESCRIPTION

FIG. 1 is a top perspective view of a purging bottle;

FIG. 2 is a first side view thereof;

FIG. 3 is a second side view thereof;

FIG. 4 is a top view thereof; and,

FIG. 5 is a bottom view thereof.

In the drawings, the broken lines depict environmental subject matter only and form no part of the claimed design.
